PRESSURE REGULATING APPARATUS

Russell A. Hetzer, Cincinnati, Ohio, assignor to
 The American Laundry Machinery Company,
 Norwood, Ohio, a corporation of Ohio

Application January 25, 1938, Serial No. 186,849

8 Claims. (Cl. 137—68)

This invention relates to a vessel or system in which a volatile liquid or solvent is being stored or utilized and more particularly to improved means for regulating pressure conditions within the vessel or system.

The object of the invention is to provide an improved apparatus for automatically compensating for otherwise wide fluctuations of pressure within a vessel or system, or in other words, for maintaining a fairly uniform pressure so that the parts of the apparatus can be designed and made of material of the proper strength but with minimum weight and cost as well as for further advantages which will more fully appear hereinafter.

In the drawing which represents one suitable embodiment of my invention:

Fig. 1 is a diagrammatic view of a dry cleaning system, parts being broken away to expose the internal structure, and showing my improved regulator in diagrammatic form associated therewith.

Fig. 2 is an enlarged cross sectional view of my improved regulator and a portion of the reclaiming unit of a dry cleaning system, showing parts of the regulator in elevation and the operating mechanism for the regulator in diagrammatic form; and

Fig. 3 is a side elevational view of a motor, showing the drive connection between the motor shaft and a pinion for operating the regulator.

One common form of dry cleaning apparatus utilizing volatile detergents comprises a chamber or casing within which garments or fabrics to be treated are subjected to the effects of a quantity of a liquid detergent, following which the liquid detergent is drained off and extracted from the fabric as much as possible and any remaining detergent is removed by the use of an air current, is condensed and returned to the liquid, and the used liquid detergent is cleaned or clarified by distillation and condensation. While any volatile detergent may be employed, one common detergent suitable for the purpose is carbon tetrachloride.

Systems of this kind if entirely closed or sealed against escape of vapors to the atmosphere necessarily must be made of heavy material. This is true not only of the casing or walls of the treating compartment but also of the walls of containers for liquid, stills, condensers and the like. The reason is that the chambers within the several vessels necessarily are subjected to widely varying fluctuations of pressure if the entire system is sealed or closed, due to the application

of heat for distillation, the variations in temperature of the outside air, and also variations in temperature of the cooling medium, such as water and the like. As a result most systems are provided with an open vent to the atmosphere to maintain atmospheric pressure or nearly so, within the system, with the disadvantage of possible loss of valuable detergent by free escape to the atmosphere. 5

The present invention is designed to prevent 10 loss of valuable detergent by escape to the atmosphere incident to the use of a vent by closing or sealing a vessel or system against venting or escape to the atmosphere except during loading or unloading and at the same time providing 15 the vessel or system with means which automatically compensate for the wide fluctuations in pressure which otherwise would be produced in such a vessel or system. In case of abnormal pressure conditions existing in the vessel or system, however, my improved apparatus acts as a vent and permits vapors to escape when the pressure becomes abnormally high or allows atmospheric air to enter the vessel or system if the pressure becomes abnormally low. 25

While my improved pressure regulating means may be employed in any vessel or system in which a volatile solvent or detergent is being stored or utilized, for purposes of illustration the system shown in the drawing comprises a treating unit 30 1, a detergent storage tank 2, a still 3, a condenser 4 and a sump tank 5 suitably connected and associated with each other.

The treating unit 1 is somewhat similar to an ordinary washing machine or drying tumbler 35 and comprises an outer casing 6 and an inner rotatable foraminous drum 7 within the chamber of the casing. Connected in circuit with the casing is a condenser 8 whose inlet side communicates by a conduit 9 with the casing 6, an 40 air moving device, such as a fan 10, the inlet side of which is connected to the condenser by means of a conduit 11, and a heater 12, the inlet side of which is connected to the outlet side of the air moving device by a conduit 13 and 45 the delivery side of which is connected to the casing by a conduit 14 provided with a valve 15.

Liquid detergent is supplied to the treating chamber by way of a supply pipe 16 having a valve 17, said supply pipe communicating with the 50 storage tank 2. The used liquid in the treating chamber 1 may be drained therefrom to a sump tank 5 by way of a pipe 18 provided with a valve 19. Sump tank 5 communicates by means of pipe 20 having a valve 21 with the evaporator or still 55

- 3 which may be heated by steam circulated through coils 22 located in the still or evaporator. The vapors or gases produced by the distilling operation in still 3 rise through a conduit 23 to chamber 24 within condenser 4, there being condensed to liquid form by the effect of cooling coil 25 through which cold water may be circulated. The liquid thus condensed flows by way of pipe 26 to the storage reservoir 2.
- 10 With this arrangement the material to be treated is first loaded into the rotating drum 7 and a quantity of liquid detergent is run into the treating compartment by opening valve 17 which is then closed. The drum 7 is rotated for 15 the proper period of time to produce a thorough agitation of the material in the detergent with a consequent washing or cleaning thereof. Finally, the drum 7 is stopped and the liquid in chamber 1 is drained to the sump tank 5 by 20 opening valve 19. When as much liquid has been extracted and drained from the work as is reasonably possible, the fan 18 is started, air from the treating chamber 1 is circulated through the condenser 8 by the fan 10, returning by the way of 25 heater 12 and conduit 14 to the treating chamber, solvent vapors being condensed and flowing by way of conduit 27 to sump tank 5. This drying operation is continued until substantially all the detergent has been recovered.
- 30 Conduit 13 is provided with a connection 28 to the atmosphere to be opened and closed by a valve or damper 29. The valve 15 in conduit 14 and valve 29 are operatively connected by means of a link 32 and may thus be jointly operated.
- 35 During the washing and drying operation before referred to the valves lie in the full line position as shown in Fig. 1. When the drying operation is finished valve 15 is moved to open position and valve 29 shuts off communication between 40 the air moving means 18 and the heater 12. Therefore when the drying operation is concluded, the fan continues to operate for deodorizing, drawing fresh air in through valve 15 from which it flows through the treating vessel 1 and condenser 8 to the atmosphere through pipe 28.
- 45 Valve 21 is now opened and the liquid in sump tank 5 is drained into the evaporator, is there distilled and is conveyed as a gas to condenser 4 from which as a liquid it drains to storage 50 tank 2.
- 55 As illustrated in the drawing the pressure within the various vessels of the system is equalized and means are provided to regulate fluctuations in pressure within the system. As shown, a vent pipe 33 leads from the sump tank 5 and is provided with a branch 34 which is connected to casing 6 and a branch 35 which is connected to storage tank 2.
- 60 When liquid is passed into the treating vessel 1 from tank 2 the vapors displaced in the treating vessel pass to tank 2 through branches 34 and 35 of the vent pipe, and when liquid is passed from treating vessel 1 to sump tank 5 vapors displaced in sump tank 5 flow to the treating vessel through 65 vent pipe 33 and branch pipe 34. In a like manner when liquid is drained from sump tank 5 into the evaporator or still 3, the vapors displaced in the evaporator pass through conduits 23 and 26 and vent pipes 35 and 33 to sump tank 5.
- 70 My present invention provides means for regulating the pressure conditions within the system and also acts as a vent when abnormal pressure 75 conditions occur within the system. As shown in Fig. 2 my improved apparatus comprises a tank 36 containing any suitable liquid, such as

water, which tank for convenience is shown mounted upon condenser 4. Arranged within the tank in spaced relationship thereto and mounted for vertical movement therein, is a container 37 having a bottom opening 38, the lower end of which container normally extends below the level of liquid in tank 36, thereby forming a gas chamber 39 into one end of which a pipe 40 extends, the other end of pipe 40 being in communication with the chamber of storage tank 2. The vertical movement of container 37 is guided by means of rolls 41 which are rotatably mounted in brackets attached to the side of the tank and are preferably spaced 90° apart and also by means of a bracket 42 having an aperture 43 through which a rack 44 secured to the container passes during the vertical movement of the container. The rack 44 is provided with a marker 45 which is placed in registry with a pointer 46 attached to bracket 42 when drum 7 is open to the atmosphere, such as when fabric is being introduced into or removed from drum 1. At this time the liquid in tank 36 and container 37 is at the same level and forms a liquid seal between gas chamber 39 and the atmosphere. In accordance with my invention means are provided to raise or lower tank 37 when the pressure within storage tank 2 or within the system tends to vary. While any suitable means responsive to pressure conditions existing within the vessel or system may be employed, as illustrated in the drawing, an electric motor 47, having a pinion 47a connected to its shaft which is in meshing engagement with rack 44, is provided and power is supplied to operate the motor in one direction when the pressure within the vessel or system tends to rise above atmospheric pressure, and in the opposite direction when the pressure within the vessel or system tends to fall below atmospheric pressure. Motor 47 is of the gear head type in which irreversible speed reducing gearing is provided, that is, the gearing not only reduces the speed at which the rack is reciprocated but prevents the rack from operating the motor.

As shown diagrammatically in the drawing the vent pipe 33 is in communication with a diaphragm 48 arranged within a housing 49, which housing also contains a mercury switch 50 supported by a bracket 51 pivotally mounted at the point 52. Extending upwardly from diaphragm 48 is a rod 53 which is connected to a lever 54 pivotally mounted at the point 55, one end of lever 54 being provided with a link 56 which is connected to one end of bracket 51 and the other end of the lever being mounted between compression springs 57 and 58 which are suitably supported in the housing.

With this arrangement, when the vapor pressure tends to rise in the system diaphragm 48 expands, moving lever 54 in a clockwise direction and tipping mercury switch 50 in an anti-clockwise direction, thereby forming an electrical connection between terminals 59 and 60 and establishing a circuit from line L₁ through conductor 61, terminal 59, mercury switch 50, terminal 60, conductor 62 and coil 63 to line L₂. The energization of coil 63 closes magnetic switch 64 and current is supplied to motor 47 from lines L₁ and L₂ by means of conductors 65 and 66. The operation of the motor raises container 37, thereby increasing the volume of gas chamber 39 and maintaining the pressure within the system substantially constant. Diaphragm 48 then contracts, the mercury switch is returned to its

normal position and the electric circuit is broken. In the event that pressure conditions within the system tend to fall, diaphragm 48 contracts, lever 54 is moved in a counterclockwise direction against the compressive force of spring 57 and the mercury switch is rotated in a clockwise direction, thereby forming an electrical connection between electrodes 67 and 68 and establishing a circuit from line L₁ through conductor 62, electrodes 68 and 67, conductor 70, coil 71 and inductor 72 to line L₂. The energization of coil 71 closes magnetic switch 73 and current is supplied to the motor from lines L₁ and L₂ through inductors 69 and 65. The motor is therefore operated in the reverse direction and tank 37 is lowered. Diaphragm 48 then expands, the mercury switch is returned to its normal position and the electric circuit is broken.

For normal fluctuations which occur in systems of this type, it is not necessary to raise the bottom opening of container 37 above the liquid level in tank 36. A breathing action is therefore provided as container 37 is raised and lowered and the pressure within the vessel or system is maintained substantially constant. In the event that the increase in volume in chamber 39 effected by raising container 37 without breaking the liquid seal does not compensate for the increase in pressure within the system, the container is raised above the level of the liquid and pipe 40 is vented directly to the atmosphere. In case abnormally low pressure conditions occur within the system, the top of container 37 is lowered against the terminal of pipe 40 and atmospheric pressure forces the liquid between container 37 and 36 downwardly a sufficient extent to allow it to flow through the bottom opening in the container.

When the top of container 37 rests upon the terminal of pipe 40, motor 47 will still continue to operate if the pressure within the system is below normal. To prevent damage by this action, motor 47 is connected to pinion 47a by means of a friction clutch, one element 75 of which is splined to the motor shaft and is yieldingly held in engagement with the other element 76, the hub of which engages a support 77. During normal operation, a compression spring 78 forces clutch element 75 into sufficient frictional engagement with clutch element 76 to translate motion from the motor shaft to pinion 47a. When the top of container 37 engages the terminal of pipe 40, however, and the motor still continues to operate, spring 78 does not exert sufficient compressive force to prevent clutch element 75 from slipping.

The pipe 40 is provided with side openings 79 which allow air to pass through pipe 40 when the top of the container 37 rests upon the end of pipe 40, and the height of tank 36, container 37, vent tube 40 and the level of the sealing liquid in tank 36 are such that during normal fluctuation of pressure within the tank or system the liquid extends above the lower end of container 37, thus forming a liquid seal which is broken if the increase in volume of chamber 39 is not sufficient to compensate for the tendency of the pressure to rise. The level of the liquid, however, should not be such that it will enter the orifice of vent pipe 40 when abnormally low pressure conditions exist in the vessel or system.

Means are also provided to maintain the liquid in tank 36 at a substantially constant level and to compensate for any liquid which evaporates. For this purpose a liquid supply conduit 82 having a

valve 83 is provided, said valve being actuated by a float 84 when the liquid in tank 36 falls below a predetermined level. An overflow pipe 85 is also provided to prevent the liquid in tank 36 from rising above a predetermined level. With such an arrangement liquid is supplied to tank 36 as it evaporates. It is also supplied to tank 36 when abnormally low pressure conditions exist in the vessel or system and the level of the liquid in the space between tank 36 and container 37 is lowered, but as such conditions generally occur suddenly, the small amount of water supplied through conduit 82 is not sufficient to raise the liquid in container 37 to such a level that it flows through conduit 40 before the vacuum conditions within the vessel or system are relieved.

To set container 37 at the proper position as indicated by the mark 45 on rack 44 and the pointer 46 on bracket 42, when normal or atmospheric pressure exists in the system, as for example when fabric is being introduced or removed from treating chamber 1, plugs 86 and 87 are provided, which are normally maintained in open position. When plug 86 is pressed, a circuit is connected in parallel with the circuit established by terminals 59 and 60 of the mercury switch and current is supplied to motor 47 to raise container 37, and when plug 87 is pressed a circuit is connected in parallel with the circuit established by the terminals 67 and 68 of the mercury switch and current is supplied to the motor to lower container 37.

What I claim is:

1. Apparatus of the class described comprising a vessel or system having a chamber containing a volatile solvent and subjected to influences tending to vary the pressure in said chamber and means for maintaining substantially uniform pressure in said chamber comprising a container having a gas chamber, motor means responsive to pressure conditions within said vessel or system for increasing and decreasing the volume of said gas chamber as the pressure within said vessel or system tends to rise and fall, and communicating means between said chambers.

2. Apparatus of the class described comprising a vessel or system having a chamber containing a volatile solvent and subjected to influences tending to vary the pressure in said chamber and means for maintaining substantially uniform pressure in said chamber comprising a container having a gas chamber, electrically operated means responsive to pressure conditions within said vessel or system for increasing and decreasing the volume of said gas chamber as the pressure within said vessel or system tends to rise and fall, and communicating means between said chambers.

3. Apparatus of the class described comprising a vessel or system having a chamber containing a volatile solvent and subjected to influences tending to vary the pressure in said chamber and means for maintaining substantially uniform pressure in said chamber, comprising a tank containing a liquid, a container having a bottom opening mounted for vertical movement in said tank, the lower end of said container being normally below the level of liquid in said tank during its vertical movement, thereby forming a liquid seal and a gas chamber in said container above said liquid, communicating means between the chamber of said vessel or system and the gas chamber of said container, and motor means responsive to pressure conditions within said vessel or system for raising and lowering said container

to increase or decrease the volume of said gas chamber when the pressure within the vessel or system tends to rise or fall.

4. Apparatus of the class described comprising a vessel or system having a chamber containing a volatile solvent and subjected to influences tending to vary the pressure in said chamber and means for maintaining substantially uniform pressure in said chamber, comprising a tank containing a liquid, a container having a bottom opening mounted for vertical movement in said tank, the lower end of said container being normally below the level of liquid in said tank during its vertical movement, thereby forming a liquid seal and a gas chamber in said container above said liquid, communicating means between the chamber of said vessel or system and the gas chamber of said container, and means responsive to pressure conditions within said vessel or system for raising or lowering said container to increase or decrease the volume of said gas chamber when the pressure within said vessel or system tends to rise and fall, said means being effective in raising said container above said liquid when the volume of said container is insufficient to compensate for the tendency of the pressure to rise in said vessel or system.
5. Apparatus of the character described comprising a vessel or system having a chamber containing a volatile solvent and subjected to influences tending to vary the pressure in said vessel or system, means for maintaining substantially constant pressure in said chamber during normal operations comprising a tank containing a liquid, a container having a bottom opening mounted for vertical movement in said tank, the open end of said container being normally below the liquid level in said tank, thereby forming a liquid seal, and its walls being spaced from the walls of said container, communicating means between the chamber of said vessel or system and the chamber of said gas container, motor means responsive to pressure conditions in said vessel or system for raising and lowering said container to increase or decrease the volume of said gas chamber when pressure conditions in said vessel or system tend to rise or fall, and means for limiting the downward movement of said container, the level of liquid in said tank

being such that when abnormally low pressure conditions occur in said vessel or system, a from the atmosphere breaks the liquid seal and vents the vessel or system.

6. Apparatus of the class described comprising a vessel or system having a chamber containing a volatile solvent and subjected to influences tending to vary the pressure in said chamber and means for maintaining substantially uniform pressure in said chamber comprising a tank containing a liquid, a container having a bottom opening mounted for vertical movement in said tank, the open end of said container being normally below the liquid level in said tank thereby forming a closed gas chamber, communicating means between the chamber of said vessel or system and said gas chamber, and electrically operated means responsive to the pressure in said vessel or system for raising or lowering said container to increase or diminish the volume of said gas chamber.

7. Apparatus of the class described comprising a vessel or system having a chamber containing a volatile solvent and subjected to influences tending to vary the pressure in said chamber and means for maintaining substantially uniform pressure in said chamber comprising a tank containing a liquid, a container having a bottom opening mounted for vertical movement in said tank, the open end of said container being normally below the liquid level in said tank, thereby forming a closed gas chamber, communicating means between the chamber of said vessel or system and said gas chamber, a diaphragm casing forming a chamber, communicating means between the chamber of said vessel or system and said diaphragm chamber, said diaphragm casing being adapted to expand when the pressure within said vessel or system tends to rise and contract when the pressure within said vessel or system tends to fall, and means responsive to the movement of said diaphragm for raising or lowering said container to increase or diminish the volume of said gas chamber.

8. Apparatus as set forth in claim 3, including means for maintaining the level of liquid in said tank substantially constant.

RUSSELL A. HETZER.
